UNITED STATES PATENT OFFICE

ROY A. BOLEY, OF INDIANAPOLIS, INDIANA, ASSIGNOR TO J. B. COLT COMPANY, A CORPORATION OF NEW JERSEY

ACETYLENE GENERATOR

Application filed June 13, 1928. Serial No. 285,084.

This invention relates to acetylene generators and more particularly to an improved reserve carbide hopper incorporated therein.

Acetylene or carbide gas generators having a main carbide hopper and a reserve carbide hopper are well known in the art, and so is an indicating means to inform the user that the main carbide hopper is empty and that the contents of the reserve hopper is being used. The indication is usually a dimming of the lights caused by a reduction in the pressure of the gas supplied by the generator. When only small quantities of carbide are successively released from the reserve hopper the dimming of the lights is either continuous or too frequent while the generator is operating on the reserve carbide supply; and if the total contents of the reserve hopper is released at one time the single accompanying indication may not be observed by the user and the carbide supply may become exhausted during the hours of darkness when it is inconvenient or even dangerous to recharge the generator. A metering device has been used to collect the carbide as it dribbles from the reserve hopper and then deliver it to the main hopper in substantial quantities, but this device is delicate in construction and unreliable in operation.

One of the objects of this invention is to so construct a reserve carbide hopper that only a portion of its total contents will be released at one time. Another object is to provide a means for controlling the carbide outlet valve of the reserve hopper so it will open quickly and release a substantial quantity of carbide each time it is opened until the reserve hopper becomes empty. Further objects are to provide a better and cheaper construction, more reliable operation, and a reserve hopper that may be easily installed in generators already in service.

One construction wherein these and other objects are attained is explained in the following description and illustrated in the accompanying drawings, in which:

Fig. 1, is a vertical section view of the upper part of a carbide gas generator embodying this invention:

Fig. 2, is an enlarged view of the improved reserve hopper and part of the main hopper; and

Figs. 3 and 4 are side and top views illustrating features of the reserve hopper.

The acetylene generator shown in Fig. 1, with which the reserve hopper comprising this invention is incorporated, is of a form well known in the art, the essential parts of which are an outer container casing 10 having a removable cover 11. Within the casing 10 is a vertically disposed cylinder 12 having its lower edge connected with the inner wall of the casing 10 by the flange 13 thereby forming a chamber 14 between the outer wall of the cylinder 12 and the inner wall of the container 10, which contains water to seal the lower edge of a gas bell 15 arranged to move up and down as the gas in the generator increases and decreases. Within the cylinder 12 is a main carbide hopper 16 having a carbide outlet 17 at the apex of the tapering bottom thereof, which outlet is controlled by a cone valve 18. The valve 18 is secured to a valve stem or feed rod 19 which extends upward through the main carbide hopper to a point where it may be engaged by the descending bell 15 to open the carbide outlet 17 to release carbide from the hopper 16 into water in the bottom of the container 10, thereby creating a sufficient quantity of gas to raise the bell. A pair of weighted levers 20 are pivoted between their ends on a pin 201 anchored in the sides of a closed mechanism box B within and near the upper end of the main hopper 16 as shown in Figs. 2 and 4. The valve stem 19 extends thru the box B and has a collar 21 rigidly secured thereto. The unweighted inner ends of the levers bear against the under side of the collar on opposite sides of the valve stem and normally tend to raise the latter so that when the bell 15 rises the valve stem 19 lifts the valve 18 to close the carbide outlet 17. The feed rod 19 extends through a tube 191 which at its upper end opens into the box B and

its lower end into the apex of a stationary cone K that is secured to the inside of the main hopper directly above the outlet 17. This cone K has its lower edge spaced from 5 the inside wall of the main hopper so as to permit carbide to flow to the outlet 17, and it also supports the carbide in the main hopper and takes its weight off the valve 18. Furthermore, the cone K cooperates with 10 the side wall of the main hopper to control the amount of carbide discharged from the reserve hopper, as will be explained later. The gas which is generated within the generator and contained in the bell may be conducted by a pipe 22 to a filter 22' and by a pipe 23 from the filter to the service pipe 15 supplying the gas consuming devices.

The improved reserve carbide hopper 24 is located in the main hopper, and both of 20 these hoppers are open at the top so that they may be charged with carbide at the same time. The reserve carbide hopper 24 is secured to one side of the box B and comprises side walls 25 and a tapering bottom 25 26. One side of the bottom has a carbide outlet 27 which is normally closed by a swinging gate 28 that has ears 281 fitting against the sides of the hopper 24. The gate 28 is hinged at its upper end, as by 30 pivots 29 which extend through the ears 281 and the sides of the hopper 24.

The gate 28 is normally held closed against the weight of carbide in the reserve hopper and is not opened until after the 35 main carbide supply is exhausted, whereupon appropriate gate-actuating mechanism automatically and suddenly operates to release the gate so that a portion of the reserve carbide will dump by gravity from 40 the reserve carbide into the main hopper, from which the carbide is fed in the usual manner to continue gas generation for a time. This dumping of carbide from the reserve hopper into the main hopper is accompanied by a momentary but very noticeable flicker of the lights, which is a signal 45 that the reserve supply is being used. When the main hopper again becomes empty another portion of the reserve supply will be 50 automatically dumped into the main hopper, accompanied by a second flickering of the lights. The reserve supply is such that this operation is repeated from six to twelve times before the reserve supply is exhausted.

55 The gate actuating and controlling mechanism may comprise a vertically movable release rod 30 that projects into the box B and is desirably parallel to the feed rod 19. The release rod 30 extends downwardly 60 through a tube or shield 31 secured in an opening in the bottom of the box B and mounted in brackets 33 on the side of the hopper 24 below the box B. The lower end of the rod carries a rounded head or enlargement 301 which normally engages the

under side of a bracket or horizontal arm 34 formed integral with one of the ears 281 or otherwise rigidly secured to the gate. The rod 30 passes freely through holes in the lower bracket 33 and the bracket 34 and its head 301 is held against the bracket 34 by a helical spring 36 located inside the shield 31 and extending around the release rod 30 into the box B. The lower end of this spring rests on the lower bracket 33, and its upper end bears against the under side of a yoke 37 secured to the rod 30. The yoke 37 has a forked end 371 which partially surrounds the valve stem 19 at a distance below and in the path of the collar 21 but within the surfaces engaged by the levers 20. The tension of the spring 36 thus normally holds the rod 30 and the yoke 37 and their uppermost position and the gate 28 in its closed position.

It will be understood that the main feed rod 19 has a certain freedom of movement downward to permit the valve 18 to function in a normal manner, which permits the main charge of carbide to feed from the main hopper without causing the reserve hopper to function. In order to insure that the gate 28 shall open suddenly and sufficiently wide to discharge a substantial quantity of carbide when the main hopper is empty, I provide an auxiliary or detaining spring 38, one end of which is secured to the side wall of the hopper 24 as at 39. This spring is coiled between its ends and then extends downwardly lengthwise of the tube 31. A bend is formed in the lower free end 40 of the spring 38 to form a catch to receive the projecting edge of the bracket 34 attached to the gate 28. The end 40 extends downwardly at an inclination to a point in line with the downward movement of the enlargement 301. The end is spaced from the enlargement and it is actuated thereby in a manner hereinafter described.

During normal operation, when the generator is charged with carbide and water and connected to suitable gas consuming devices it operates as follows: As gas is drawn from the delivery conduit 23 the gas bell 15 descends and as it approaches the lower limit of its movable range the inner surface of the top of the bell strikes the top of the feed rod 19 and forces it and the valve 18 downward against the upward pressure of the weighted levers 20, thereby opening the carbide outlet 17 of the main carbide hopper 16 and releasing carbide from the main carbide hopper into the water in the container 10. As the carbide encounters the water, gas is evolved which creates a pressure within the bell 15, forcing it upward. As the bell rises the weighted levers 20 bearing against collar 21 force the rod 19 and valve 18 upward thereby closing the carbide outlet 17 so no more carbide will be released.

from the main hopper until the bell again descends. This cycle of operation continues until the supply of carbide in the main carbide hopper 16 has become exhausted.

5 When the gas bell 15 again descends, after the supply of carbide in the main hopper is exhausted, it engages the top of the feed rod 19 and forces it downward as before thereby opening the carbide outlet of the main carbide hopper. As the main hopper is empty and no carbide escapes to create gas to raise the bell, both the bell and the rod 19 continue to descend. When the collar 21 on the descending rod 19 encounters the top of the 10 yoke 37, this yoke and the rod 30 are forced downward, together with the parts already descending, against the added resistance of the upward pressure of the spring 36. The resistance of the spring 36 momentarily 15 retards the descent of the bell 15 and reduces its effective weight to such an extent that the gas pressure within the generator and the service pipes is materially reduced thereby causing a very noticeable temporary dimming of the lights supplied by the generator and this indicates to the observant user that the supply of carbide in the main carbide hopper is exhausted and that the reserve supply of the carbide is about to be drawn 20 upon. As the rod 30 descends the spring 38 holds the gate 28 closed and delays its release until the head 301 on the lower end of the rod 30 engages the lower end 40 of the spring 38 and forces it out of engagement with the arm 34 on the gate 28, allowing the gate to suddenly open a substantial distance whereby a substantial quantity of carbide is quickly dumped by gravity from the reserve carbide hopper 24 into the main 25 carbide hopper 16. The position of the reserve hopper outlet is desirably just above the usual stationary carbide supporting cone K in the main carbide hopper, and is so spaced from the wall of the main hopper as 30 to assist in controlling the quantity of reserve carbide dumped into the main hopper.

As the carbide outlet for the main hopper is open at the time carbide is dumped from the reserve hopper, some of the dumped carbide passes directly through the outlet 17 into the water in the container 10 thereby generating a quantity of gas which raises the bell 15. The mechanism for releasing and reclosing the reserve hopper gate is so 35 constructed and arranged that the short time interval elapsing, from the opening of the gate, while reserve carbide is descending to the water, and until sufficient gas is generated to raise the bell off the feed rod 19, will 40 be sufficient to allow a predetermined quantity (say, about a pound) of reserve carbide to discharge from the reserve hopper. As the bell rises the spring 36 forces the yoke 37 and the rod 30 upward until the spring 45 40 and the head 301 of the rod 30 have

closed the gate 28 by their upward pressure against the edge and under side of the arm 34 attached to the gate, the spring 36 itself being of such strength that it will readily close the gate against the entire weight of carbide in the reserve hopper.

The gate 28 thus opens more rapidly than the bell descends and closes as and at substantially the same speed that the bell ascends. As the bell rises still higher the action of the weighted levers 20 against the collar 21 closes the carbide outlet for the main hopper as already described. The main hopper now contains a small supply of carbide and the generator will, for a comparatively short period, function the same as when the original supply of carbide in the main carbide hopper was being used. In the meantime, the spring 36 has operated to reclose the gate against the weight of the remaining carbide in the reserve hopper, and spring 38 with its free end 40 as well as the rest of the gate-controlling mechanism are automatically restored to their initial position, ready to repeat the operation. It will be evident that substantially the same small quantity of carbide will be dumped from the reserve hopper every time the gate opens, because the time interval between the release of reserve carbide and the generation of sufficient gas to raise the bell and permit the gate to reclose will be substantially constant.

When the supply of reserve carbide dumped into the main hopper is exhausted, the bell will again automatically descend and similarly dump another quantity of carbide from the reserve hopper and at the same time the lights will flicker as already described. This cycle of operation will continue until the carbide is exhausted from both the main and reserve hoppers.

The arrangement of the reserve hopper so it dumps only a portion of its total contents when its outlet is opened is of considerable importance. If the total contents of the reserve hopper were dumped at the first opening of the gate 28, the accompanying indication might be given during daylight hours when a gas stove was being used, and, therefore, would probably not be observed by the user. As a consequence the entire carbide supply might become exhausted during the hours of darkness when it was inconvenient or even dangerous to refill the generator. But in the operation of the generator described herein, where the indication that the supply of carbide in the generator is low is given several times, one or more of the indications are quite sure to be given while lights are burning, which flickering would be observed by the user in time to refill the generator in daylight. The auxiliary spring 38 is therefore an important feature, especially where the generator is used for house lighting, for without such

spring the gate 28 would be opened somewhat as soon as the release rod 30 moves down and a small quantity of carbide would be fed directly to the generating chamber. 5 This quantity would vary with the load carried by the generator and there would therefore be no signal to the user, since the carbide would dribble from the reserve hopper and the generator would function practically as it did when the main carbide supply was being used.

10 The reserve carbide hopper is designed so the generator functions as though it contained no reserve hopper as long as there is carbide in the main hopper. If the bell is vented very rapidly when the main hopper still contains carbide, the mass of carbide lying against the outside of the door will keep the latter closed even though the bell moves to its lowermost position. In that 15 event the reserve hopper rod 30 and spring 40 may be forced into carbide in the main hopper but will resume their normal position later without discharging carbide from the reserve hopper or in any way 20 damaging the mechanism or interfering with its function later on. Accordingly, the gas bell may move to its lowermost position at any time without injuring or disarranging any of the operating parts of the generator, and when the bell again rises all operating parts are automatically restored to their normal operating positions without 25 requiring manual resetting or restoration. 30 As long as there is carbide in the main hopper the outlet for the reserve hopper can not be opened even though the bell goes to an abnormally low position due to a sudden venting of gas from the generator, therefore, 35 the supply of carbide in the reserve hopper remains intact until after the supply of carbide in the main hopper is exhausted. This prevents the carbide supply from becoming exhausted through abnormal operating conditions without indicating to the user that 40 the supply is low.

45 The improved reserve hopper may be incorporated with a generator when it is first assembled, or such hopper may be assembled as a unit and readily secured in place in the main hopper of an acetylene generator already in service. Various changes in the structure and arrangement of the apparatus shown herein may be made without departing 50 from the invention.

55 I claim:

1. In an acetylene generator, the combination of a main carbide hopper; a gas bell; a reserve carbide hopper comprising a discharge opening normally closed by a gate; 60 mechanism operable by said bell for opening said gate; mechanism operated by a yieldable means for closing said gate against the pressure thereon of the carbide in said hopper; and a device operable by said mechan-

ism to suddenly release said gate to discharge reserve carbide into said main hopper.

2. In an acetylene generator, the combination of a reserve carbide hopper having a discharge opening normally closed by a gate; a main carbide hopper having an outlet; a feed valve controlling said outlet; a movable operating rod for said valve; and mechanism for operating said gate comprising spring means tending to hold said gate in a closed position, a device compressible against the pressure of said spring means to release said gate, and means on said operating rod normally spaced from said device whereby said operating rod during part of its movement is adapted to move independently of said device and during another part of its movement is adapted to depress said device.

3. In a carbide gas generator, the combination of a main carbide hopper having an outlet; a feed valve controlling said outlet; an operating rod for said valve; a collar fast on said rod; means bearing against said collar tending to lift said rod and valve; a reserve carbide hopper having a discharge opening normally closed by a gate; and mechanism whereby said gate is adapted to be operated by said rod, such mechanism comprising a device connected to said gate, an arm on said device engageable by said collar, a spring tending to move said device to close said gate, and a second spring tending to close said gate but operable by said device to release the gate.

4. In an acetylene generator, a main carbide hopper, means for intermittently discharging carbide therefrom until said hopper has been discharged; a reserve carbide hopper having an opening for intermittently discharging carbide into the main hopper when said main hopper is substantially empty; means for controlling said reserve discharge comprising a gate for said opening adapted to be retained in a closed position by the carbide in the main hopper, a catch for retaining the gate in a closed position, yieldable means for actuating said gate to a closed position against the pressure on said gate of the carbide in said reserve hopper and means responsive to a reduced pressure in the generator for actuating the yieldable means to the gate open position and to release said catch.

5. In an acetylene generator, the combination of a main carbide hopper; a gas bell; a reserve carbide hopper having a discharge opening therein; means for normally closing said opening; a catch for normally retaining said closure means in a closed position, mechanism operated in response to the pressure in said gas bell to release said catch; and yieldable means cooperating with said

mechanism to restore said closure means to its normally closed position.

6. In an acetylene generator, the combination of a main carbide hopper; a gas bell; 5 a reserve carbide hopper having a discharge opening therein; means for normally closing said opening; a catch for normally retaining said closure means in a closed position; a rod operated in response to the pressure in 10 said gas bell to release said catch after a predetermined movement; and a yieldable means resisting the movement of said rod to release said catch and coacting with said rod to restore said closure means to its normally 15 closed position against the weight of the carbide in said reserve hopper after a portion of said reserve carbide is released.

7. In an acetylene generator, the combination of a main carbide hopper; a gas bell; 20 a reserve carbide hopper having an opening therein adapted to discharge carbide into said generator; a gate for said opening, said gate being adapted to be opened by the weight of the carbide thereon; a catch for 25 retaining said gate in a closed position; a mechanism operated in response to the gas pressure in said gas bell for operating said catch to release said gate; a loss motion connection between said mechanism and said 30 gate adapted to permit said mechanism to move a predetermined distance before releasing said gate and thereby permit said gate to freely open; a yieldable means co-operating with said mechanism for actuating 35 said gate to its closed position and said catch to its gate retaining position upon discharging carbide from said reserve hopper.

8. In an acetylene generator, the combination of a main carbide hopper; a gas bell; 40 a reserve carbide hopper having an opening therein adapted to discharge carbide into said generator; a gate for said opening, said gate being adapted to be opened by the weight of the carbide thereon; a catch for 45 retaining said gate in a closed position in opposition to said yieldable force; a mechanism operated by said gas bell for operating said catch to release said gate; a loss motion connection between said mechanism and said 50 gate adapted to permit said mechanism to move a predetermined distance before releasing said gate and thereby permit said gate to freely open in response to said yieldable force; a yieldable means for resisting the descent of said gas bell and thereby reducing the pressure within said gas bell; a 55 yieldable means cooperating with said mechanism for actuating said gate to its closed position and said catch to its gate retaining position upon discharging carbide from said reserve hopper.

9. In an acetylene generator, the combination of a main carbide hopper; a reserve carbide hopper comprising a normally closed 60 gate operable to dump carbide from said

reserve hopper into said main hopper; controlling means adapted to release said gate from closed position; and detaining means adapted to delay the opening of said gate until said controlling means has moved to 70 substantially the full open position of said gate.

10. In an acetylene generator, the combination of a main carbide hopper; a reserve carbide hopper comprising a normally closed 75 gate; and mechanism adapted to suddenly release said gate to dump a portion of the carbide in the reserve hopper into the main hopper.

In testimony whereof, I affix my signature. 80
ROY A. BOLEY.
